UNITED STATES PATENT OFFICE.

ALLEN KISSAM, OF ORLANDO, FLORIDA.

PROCESS FOR FILLING AND TAMPING MOLDS.

Application filed June 27, 1924. Serial No. 722,842.

To all whom it may concern:

Be it known that I, ALLEN KISSAM, citizen of the United States, residing at Orlando, in the county of Orange and State 5 of Florida, have invented certain new and useful Improvements in Processes for Filling and Tamping Molds, of which the following is a specification.

This invention relates to a process for 10 making concrete blocks or the like, and has particular reference to the filling of molds with concrete or other cementitious materials and at the same time tamping or compacting said materials as the mold is being 15 filled.

To that end, the invention has in view 20 a process which may be carried into effect with the aid of simple and practical apparatus to fill molds of the type used in the concrete products industry for the production 25 of hollow building blocks from semi-wet concrete, that is concrete which is too dry to flow, but wet enough to stick together the same therein, or otherwise positioning the same to sufficient pressure.

A further and more specific object of the 30 invention is to provide a process which aims to fill various sizes and shapes of molds with semi-wet concrete and simultaneously compacting the same therein with speed and economy, thereby facilitating production on a practical and feasible commercial scale.

In carrying the present invention into effect, it will, of course, be understood that 35 any suitable and convenient type of apparatus may be employed, but by way of example, a preferred and practical type of apparatus is shown in the accompanying drawings, in which:—

Figure 1 is a vertical sectional view of one type of apparatus employed in practicing the process.

Figure 2 is a side elevation of the apparatus shown in Fig. 1.

Figure 3 is a horizontal cross sectional view taken on the line 3—3 of Fig. 1.

Figure 4 is a top plan view of the mold shown in Fig. 1.

As previously indicated, the present invention relates to a process for the filling of molds with semi-wet cementitious materials by projecting such material with sufficient force into the mold to tamp or compact the material in the mold without the necessity of involving a separate tamping

operation, thereby greatly expediting the formation of the blocks. For the purpose of accelerating the movement of the semi-wet material in its movement toward the 60 mold, fluid under pressure is utilized, the same being susceptible of ready control and also offering the advantage of using different fluids such as compressed air, gas, steam or vapor, where the circumstances require 65 and the nature of the installation permits.

Referring to the drawings, which illustrate one form of apparatus, for carrying the process into effect, it will be observed that the mold is designated generally as A 70 and is provided with the cores B which provide the block forming channels C. This mold A operates in conjunction with a material projecting device designated generally as D and including in its organization 75 a casing 1 having a feeding hopper 2 at the upper end thereof which communicates with a charge or increment holding compartment 3 intended to hold a measured amount of concrete. The compartment or chamber 3 has its bottom wall formed by the sliding gate members 4—4 which meet at the center of the compartment and may be manipulated from opposite sides of the casing while the top of said compartment is formed by a cut-off plate 5 clearly shown in Figs. 1 and 2 of the drawing.

The casing 1 below the chamber 3 constitutes a shaping and guiding tube whose horizontal cross section members correspond 90 to the horizontal cross section of the block to be made, or in other words must go inside with the formation of the mold A. Therefore, the guiding tube portion of the casing 1 is provided with the core members 95 6 and 7 which give the moving material the desired shape. In the drawing the cores are rectangular in horizontal cross section and the vertical sides 8 thereof are arranged to form the relatively constricted passages 100 9. These passages are preferably slightly narrower at the lower ends 9^a due to the fact that the sides of the casing 1—1 converge downwardly to a sufficient degree to provide the relatively constricted discharge 105 orifices adjacent the mold A. The upper ends of the cores 6 and 7 are provided with the converging wall portions 10 which converge to provide the material distributing points 11—11, the said points or tips 11—11 110 being arranged and disposed so as to divide the transverse width of the casing 1 into

equal shapes thereby assuring each of the passages 9 receiving an equal quantity of material. If desired the walls 10-10 may be made conical, the main point being to 5 provide converging passages 12 which communicate with the passages 9. The cores 6 and 7 are held in place within the tube 1 by two thin metal strips 13 running through both cores and also through the sides of 10 the tube 1 as clearly shown in Figs. 1 and 3. Due to the fact that strips 13 present in effect knife edges to the material, the flow of the latter is not obstructed.

The fluid pressure means employed preferably consists of a pressure trunk 14 surrounding the casing 1 and having an intake line 15 connected therewith, the same being provided with an operator's control valve 16. This trunk 14 is preferably located on 15 the outside of the casing 1 at a point where the passages 12 join the passages 9 and the said trunk 14 communicates with said passages 9 by an ejector port 17 which extends entirely around the casing 1, and whose 20 sides diverge slightly in the direction of flow. The trunk or manifold 14 also supplies fluid under pressure to the flues 18 which communicate with the upper end of the compartment 3. These flues are relatively wide as will be observed from Fig. 2 25 and serve to supply pressure to the compartment 3 to get behind the material therein and force it into the passages 12 when the slides or gates 4-4 are opened.

The operation of the device is as follows: The hopper 2 is supplied with concrete by any suitable means such as a conveyer. Slide 5 is drawn out and material falls into compartment 3. Slide 5 is then closed and the 30 weight of concrete in hopper 2 effectually seals compartment 3 from above. Slide 5 is set a sufficient distance above slides 4-4 to allow 3 to hold a sufficient amount of material to make a block. Valve 16 is now 35 opened and a stream of gas flows into 14 thence through 17 into passages 9 and through the outlets 9a. Gas also flows through flues 18 into compartment 3 on top of concrete. Slides 4-4 are now smartly 40

pulled apart but not too rapidly. If opened too rapidly, gas above concrete in 3 would blow it out of 3 so fast it would tend to jam in passages 9. Experience will soon teach the operator how fast to open slides 45 4-4. As slides 4-4 are opened concrete is blown out of 3 into 12 and is distributed or given the desired horizontal cross section by cores 6 and 7. The stream of gas issuing through port 17 increases the velocity 50 of the moving concrete in passages 9 and elongates said moving concrete in the direction of its motion, thus obviating any tendency of concrete to jam in 9. It is thus seen the action is very similar to the charge 55 in a shot gun barrel with the exception of

the action of gas issuing through 17 as noted. It is advantageous to have sides of the tube converge slightly at 9a as the gas tends to expand in horizontal cross section at 9a. At 9a and beyond, the gas separates 70 to a large extent from the mixture, the concrete due to its greater inertia continues into mold and is compacted therein by the tamping action of the particles themselves due to their very high velocity. Valve 16 75 is now closed and also slides 4-4 and the operation can be repeated as soon as mold is empty.

Steam is greatly to be recommended as the fluid employed for several reasons. First 80 it can be generated without the use of fans or pumps. Secondly, its water and heat content help to accelerate the set of the concrete. Thirdly, that which is entrapped in the molded concrete will on condensing draw 85 the particles of concrete together, and last but not least, a velocity of three hundred to four hundred feet per second can be acquired by its use. However, any gas or vapor could be used. 90

From the foregoing, it will be understood that the present invention aims to project or "shoot" the semi-wet material into the mold A. The material is first measured in the compartment 3 and then subjected to pressure at the top of the compartment so as to present the material constituting the charge against the gates 4-4. The quick opening of the gates releases the material which falls evenly into the passages 12 and when the material reaches the zone of the accelerating blast fed through the port 17, the material will be broken up into an elongated stream and sent with considerable force through the passages 9 into the corresponding compartments of the mold A. 100

It will of course be understood that various changes may be made in the apparatus employed, and also that the process can be practiced with different forms of construction without in anyway departing from the spirit of the invention or scope of the appended claims. 105

I claim:

1. A process for the filling of molds with 115 semi-wet cementitious materials which consists in forcing by fluid pressure a quantity of said material through a tube into a mold beyond, the tube and mold having the same cross sectional shape.

2. A process for the filling of molds with semi-wet cementitious materials which consists in forcing by fluid pressure a quantity of said material through a tube into a mold 120 beyond, the tube and mold having the same cross section, and while the mass is in motion in the tube to expose the same to the accelerating action of a blast of air or equivalent fluid. 125

3. A process for the filling of molds with 130

semi-wet concrete or other similar cementitious materials in a dense compact condition by blowing a measured amount of said material through a tube which will give 5 said material while in motion a cross section similar to the cross section of article to be molded, and accelerating the movement of said material by the force of a blast of gas or vapor, to such a velocity that

the impact developed upon striking mold 10 and particle of material behind striking particles of material in front, in direction of their motion, will fill mold with said material in a dense compact condition.

In testimony whereof I hereunto affix my 15 signature.

ALLEN KISSAM.
